AU 292
OP D 16.979

EX

UNITED STATES PATENT OFFICE.

FRANK S. JOHNSON, OF SAN FRANCISCO, CALIFORNIA.

DESIGN FOR AN INSIDE WRAPPER FOR DRIED FRUIT.

SPECIFICATION forming part of Design No. 16,979, dated November 9, 1886.

Application filed September 7, 1886. Serial No. 212,946. Term of patent 14 years.

To all whom it may concern:

Be it known that I, FRANK S. JOHNSON, a citizen of the United States, residing at the city and county of San Francisco, State of California, have invented and produced a new and original Design for Inside Wrappers for Dried-Fruit and Raisin Boxes, of which the following is a specification, reference being made to the accompanying drawing.

10 My design is for a wrapper for raisins or dried fruits; and it consists of an ornamentation representing maiden-hair fern extending nearly from end to end on each side, and having two campion roses intertwined with the fern, 15 one rose being placed near each end of the intertwined fern on the one side, and three roses in the center of the other side. The short ends of the wrapper also have the representation of maiden-hair fern intertwined and extending

across them, with two roses intertwined therewith. These ornamentations are usually printed or otherwise impressed on the wrapper, as shown in the specimen hereto annexed.

Having thus described my invention, what I claim as new, and desire to secure by Letters Patent, is—

A design for inside wrappers for dried-fruit boxes, consisting of the foundation representation of maiden-hair fern intertwined upon the sides and ends of the wrappers, and having 30 campion roses or buds intertwined therewith, as shown.

In witness whereof I have hereunto set my hand.

FRANK S. JOHNSON.
